UNITED STATES PATENT OFFICE.

ELLIOTT E. FURNEY, OF ST. LOUIS, MISSOURI, ASSIGNOR OF ONE-HALF OF HIS RIGHT TO DARWIN L. SKIDMORE AND CHRISTOPHER C. HARRIS, OF SAME PLACE.

HATCHWAY.

SPECIFICATION forming part of Letters Patent No. 223,284, dated January 6, 1880.

Application filed August 8, 1879.

To all whom it may concern:

Be it known that I, ELLIOTT E. FURNEY, of St. Louis, Missouri, have made a new and useful Improvement in Elevators, of which the following is a full, clear, and exact description, reference being had to the annexed drawing, making part of this specification, in which an elevator having the improvement is shown in perspective.

10 The present invention relates to an improved construction for closing the hatchways of an elevator-shaft saving when the car is passing; and it consists, mainly, in peculiarly constructed and arranged hatches, in combination with a car provided with means for operating the hatches, substantially as hereinafter described.

Referring to the drawing, A represents the elevator-car, which, saving as modified by the present improvement, may be of the ordinary 20 description. B B' represent the usual guides, and C C' portions of floors of successive stories of the building.

E E' E' are the hatches or doors used to close the hatchways. The hatches are hinged 25 at e e' e' to brackets F F' F', which depend from the floors C C', respectively, the level of the hinges being sufficiently low and the hatches of suitable size to cause the latter, when closed, to be inclined together, as shown, 30 and when opened, either by an ascending or descending car, to be turned back against or toward the brackets F F'.

The hatches are preferably made imperforate and to close closely together, and they 35 are cut away at their corners e² e² to fit around the guides C C'. The brackets F F' are also preferably in the form of close partitions or walls, for while an open-work construction might answer to prevent things from falling 40 through the hatchways, it would not cut off the passage of fire and smoke.

At their upper edges, e³ e³, the hatches are furnished with lips or flanges e⁴ e⁵, which extend upward from the edges e³ e³, and which 45 flare from each other, as shown, the lips e⁴ diverging from the lips e⁵. The lips may extend the entire length of the edges e³, if desired.

The car A, on its under side, and at points

opposite the lips e⁴ e⁵, is furnished with wedge-shaped projections a a. On its top it is preferably provided with projections a' a', that may be in the form of rollers, and which are arranged to encounter the under side of the hatches as the car is elevated.

The operation is as follows: As the car rises the rollers a' a', coming against the hatches overhead, cause the latter to be turned on their hinges and opened apart sufficiently for the car to pass. As soon as this has occurred the hatches, being properly balanced therefor, fall together again, closing the hatchway. As the car descends the projections a a enter between the diverging lips e⁴ e⁵, causing the hatches to be turned back toward the 65 brackets, and permitting the car to pass down between them. The hatches then close together again, as before.

The principal advantage of the present device is, that by reason of the mode of hanging the hatches as described, the floors do not need to be cut into to provide room for the hatches when opened, and no space is occupied by the hatches that is needed for other purposes.

A further advantage is this: The hatches do not open downward by any object falling upon them, and do not open at all unless a wedge is inserted between the edges e³ e³.

The brackets can be so made and arranged, 80 as well as the hatches, as to provide space into which things falling onto the hatches may roll and not be crushed by the hatches in opening.

The rollers or projections a' a' may be arranged to strike the hatches at or near the edges e³ e³, instead of near the hinges, as shown, and, so far as lifting the hatches is concerned, the invention is operative without using any projection whatever upon the upper 90 end of the car. It is much better, however, to employ some kind of projection, and in the form of rollers, as shown.

In case the edges e³ e³ of the hatches are sufficiently apart for the projections a a to 95 enter between and open the hatches apart, the flaring lips e⁴ e⁵ may in some cases be dispensed with.

I am aware that elevator-hatches have been forced horizontally apart by means of wedge-shaped projections upon the car, and that they have been arranged to turn up and turn down 5 by the ascent and descent, respectively, of the car; but as the first-named construction would require the floor to be cut into to provide room for the hatches when opened, and as the last—that is, hatches which turn down—would be 10 opened by any falling object, neither of such constructions would answer my present purpose, and I disclaim them.

I claim—

1. The combination of the car A, having 15 the wedge-shaped projections *a a*, the hatches E E, and the brackets F F, said hatches, both when the car is descending as well as ascending, turning upon the hinges *e e* against or toward the brackets, for the purposes set forth, 20 and substantially as described.

2. The combination of the car A, having the projections *a a*, the hatches E E, having the lips *e⁴ e⁵*, and the brackets F F, said hatches, both when the car is descending as well as ascending, turning upon the hinges *e e* against 25 or toward the brackets, for the purposes set forth, and substantially as described.

3. The combination of the car A, having the projections *a a* and *a' a'*, the hatches E E, having the lips *e⁴ e⁵*, and the brackets F F, said 30 hatches, both when the car is descending as well as ascending, turning upon the hinges *e e* against or toward the brackets, for the purposes set forth, and substantially as described.

Witness my hand.

E. E. FURNEY.
